STOKER MECHANISM

Howard P. Anderson, Erie, Pa., assignor to The Standard Stoker Company, Incorporated, a corporation of Delaware

Application January 3, 1935, Serial No. 211

4 Claims. (Cl. 198—15)

My invention relates to improvements in stoker conveyor troughs and more particularly to cast steel troughs for locomotive tenders, of the type shown in Patent No. 1,920,754, issued to W. L.

5 Lentz et al.

The length of the conveyor trough used in a particular stoker installation depends upon the type of tender and the length of its fuel bin and therefore may vary anywhere from twelve to 10 fifteen feet. This necessitates the use of a number of large and expensive patterns. It is therefore an object of my invention to provide a stoker conveyor trough comprising a forward cast section, a rearward cast section and an intermediate 15 cast section, so designed that the forward and rearward castings are of standard construction regardless of the length of the trough, and only the intermediate section, which is a simple and relatively cheap casting, is variable.

20 It is another object of my invention to provide a sectional stoker trough of the type described above with novel and improved splicing means whereby the sections when assembled will form a rigid, compact and durable unit.

25 With the above and other objects and advantages in view, the invention consists in the features of construction, the combination of elements and arrangement of parts hereinafter more fully described and claimed, and illustrated in 30 the accompanying drawing, in which,

Figure 1 is a longitudinal vertical central section through the conveyor trough;

Figure 2 is a top plan view of the structure shown in Figure 1;

35 Figure 3 is a sectional view on the line 3—3 of Figure 1 with the splice plate in position;

Figure 4 is a sectional view on the line 4—4 of Figure 1;

40 Figure 5 is an enlarged fragmentary view of the structure shown in Figure 3 with the splice plate removed; and

Figure 6 is an isometric view of the splice plate.

In the drawing is shown a stoker trough, designated as a whole by the numeral 10, adapted to 45 be mounted beneath the tender fuel bin 11 of a locomotive tender. The trough 10 is provided with an open mouth 12 through which fuel passes from the bin 11. In stoker installations in which it was found to be necessary or desirable to use 50 cast steel troughs, as, for example in the water bottom type of tender, it has been customary to form the trough as a single casting. Since these troughs constitute large, bulky and heavy castings, being anywhere from 12 to 15 feet in length 55 and weighing about 6000 pounds, a heavy invest-

ment in machine tools is necessary for properly performing the finishing work. Then, too, since the troughs vary in size depending upon the particular installation, a number of large and expensive patterns are required.

These disadvantages are, to a large measure, overcome in my novel sectional cast steel trough. Referring to the drawing, the trough 10 comprises a rear section 13, a front section 14 and an intermediate section 15, arranged to be assembled 10 and spliced in a novel manner, described hereinafter in detail.

The rear section 13 of the trough 10 has cast therewith a gear box 16, for housing stoker drive mechanism, forming a closure for the rearward 15 end of the trough. The front section 14 of the trough 10 has cast therewith a transverse end plate 17, forming a closure for the forward end of the trough. A bearing 18 is formed in the gear box 16, arranged to receive the shaft of a 20 conveyor screw (not shown), and the end plate 17 is provided with an opening 19 through which the fuel carried forward by the conveyor screw is delivered. The end sections 13 and 14 constitute the heaviest and most expensive castings of the 25 sectional trough, and the present invention permits them to be made of a standard design and construction irrespective of the length of the trough. The intermediate section 15 of the trough 10 is a relatively simple casting, and its 30 length is therefore made to vary depending upon the desired length of the trough.

It is apparent therefore that regardless of the length of the trough, a standard pattern may be used for the complicated end castings and only 35 for the intermediate casting is it necessary to have a number of patterns.

The sections 13, 14, and 15, except for their 40 end portions, are uniform in cross sectional configuration. As best shown in Figure 4, the trough 45 has a rounded bottom 20 to conform to the periphery of the conveyor screw (not shown) mounted in the trough, and side walls 21 and 22, diverging as they extend upwardly from the round trough bottom and then continuing vertically upward. The side walls 21 and 22 are provided with horizontally inwardly extending ledges 23 and 24, respectively; and diverging flanges 25 and 26 extend upwardly from the outer edges of the ledges 23 and 24, respectively. The 50 ledge 23 is provided with the seats 27 and 28, and the ledge 24 is provided with the seats 29 and 30. In the seats 27 and 29 are secured, preferably by welding, the inwardly extending plates 31 and 32 respectively, forming with the seats 27 and 29, 55

respectively, the guideways 33 and 34. Slide plates (not shown) normally forming a closure for the open mouth of the trough are adapted to slide in the guideways 33 and 34, whereby they 5 may be drawn forwardly from covering position to provide an opening through which fuel falls into the trough 10.

Side sheets 35 and 36, arranged to form the side walls of the fuel bin 11, are secured, preferably 10 by welding, to the diverging flanges 25 and 26, respectively, and the rear sheet 37, forming the rear wall of the fuel bin, is secured, also preferably by welding, to the gear box 16.

The adjacent end portions of the sections 13, 15 14 and 15 are each slightly enlarged and are substantially V-shaped in cross section, the bottom of the V however being rounded. Thus when the sections 13, 14 and 15 are placed end to end, there is formed at the adjacent ends of the sections 13 and 15 a depression 38 in the trough bottom and side walls, and at the adjacent ends of the sections 14 and 15 a depression 39. In each of these depressions is fitted a splice plate 40, the thickness of which is equal to the depth 25 of the depressions 38 and 39, so that the splice plates 40 form continuations of the inside surface of the trough walls. A continuous weld extends around the sides and bottom of the trough at the adjacent ends of the sections 13, 14 and 15 30 rigidly securing them together and securing the splice plates 40 in place. A continuous weld also extends along the marginal edges of the splice plates where they contact the trough. The adjacent edges of the sections 13, 14 and 15 are 35 preferably chamfered as at 41 and the walls defining the depressions 38 and 39 are preferably beveled as at 42.

The splice plates 40 are provided with inwardly extending ledges 43 and 44, which may be formed 40 integral with the splice plate 40 or if separable may be welded thereto. The ledges 43 and 44 form continuations of the ledges 23 and 24.

The sections 13, 14 and 15 and splice plates 45 40 when assembled and welded form a rigid, tight and compact trough. By forming the trough in sections, simpler and less expensive machinery 50 may be employed in performing the machining operations on the trough. The sections of the trough may be assembled and welded together before or after being installed on the tender.

I claim:

1. A sectional conveyor trough comprising a plurality of end-to-end related sections having 55 enlarged end portions at their respective adjacent ends forming enlargements in said trough, said trough having a rounded bottom and diverging side walls, the side walls of the unenlarged portions of said trough having longitudinal inwardly extending ledges restricting the open mouth of 60 said trough and having seats formed therewith,

a splice plate fitted in each of said enlargements overlapping the adjacent enlarged end portions of said sections, said splice plates being provided with longitudinal inwardly extending ledges forming continuations of said first named ledges, 5 said sections and splice plates being united in rigid relationship by means of welding.

2. A sectional conveyor trough comprising a plurality of end-to-end related sections having 10 enlarged end portions at their respective adjacent ends forming enlargements in said trough, said trough having a rounded bottom and diverging side walls, the side walls of the unenlarged portions of said trough having longitudinal inwardly extending ledges restricting the open 15 mouth of said trough and having seats formed therewith, a splice plate fitted in each of said enlargements overlapping the adjacent enlarged end portions of said sections, said splice plates being provided with longitudinal inwardly extending ledges forming continuations of said first 20 named ledges, a continuous weld joining the adjacent edges of said sections and continuous welding along the junction of the marginal edges of said splice plates and the inner wall of said 25 trough.

3. A sectional conveyor trough including two end-to-end related sections having enlarged end portions at their respective adjacent ends forming an enlargement in said trough, said trough having a rounded bottom and diverging side walls, the side walls of the unenlarged portions of said trough having longitudinal inwardly extending ledges restricting the open mouth of said 30 trough and having seats formed therewith, a splice plate fitted in said enlargement overlapping the adjacent enlarged end portions of said sections, said splice plate being provided with longitudinal inwardly extending ledges forming 35 continuations of said first named ledges, said sections and splice plate being united in rigid relationship by means of welding.

4. A sectional conveyor trough including two end-to-end related sections having enlarged end 45 portions at their respective adjacent ends forming an enlargement in said trough, said trough having a rounded bottom and diverging side walls, the side walls of the unenlarged portions of said trough having longitudinal inwardly extending ledges restricting the open mouth of said trough and having seats formed therewith, a splice plate fitted in said enlargement overlapping the adjacent enlarged end portions of said sections, said splice plate being provided with 55 longitudinal inwardly extending ledges forming continuations of said first named ledges, and means rigidly uniting the splice plate to said sections.
